Primary Examiner — John Windmuller*Assistant Examiner* — John R Yeh(74) *Attorney, Agent, or Firm* — Buchanan Ingersoll & Rooney PC(57) **CLAIM**

The ornamental design for a stake for holding decorative light, as shown and described.

DESCRIPTION

FIG. 1 is a front perspective view of our stake for holding decorative light in which the light bulb socket holding portion is in a vertical position,

FIG. 2 is a front view thereof;

FIG. 3 is a top view thereof;

FIG. 4 is a left side view thereof;

FIG. 5 is a rear perspective view thereof;

FIG. 6 is a bottom view thereof;

FIG. 7 is a rear view thereof;

FIG. 8 is a right side perspective view thereof; and

FIG. 9 is a perspective view thereof showing the light bulb socket holding portion is in a horizontal position.

FIG. 10 is a front view thereof.

FIG. 11 is a top view thereof; and,

FIG. 12 is a left side view thereof.
